ABSTRACT OF THE DISCLOSURE

The present invention relates to improvements in guide channel follower devices for use in association with the margin of a slidable panel, as for example the lower edge of a door panel adapted to be shifted along a guide channel. An embodiment of the invention disclosed in this application consists of a plate-like fitting adapted to be fastened as by screw fasteners to the lower edge of a door panel, the central portion of said plate-like fitting having a bearing or bushing extending upwardly therefrom and insertable within a complementary aperture of the lower margin of the panel. A shank member is longitudinally slidable within the bearing, the outer or projecting portion of the shank supporting a follower member such as a roller. Encircling the shank and positioned between the roller and the plate member is a spring biased in compression so as to continually urge the roller downwardly, whereby to maintain continuous proper registration of the roller with the channel of a guideway or track.

It has heretofore been common practice in the manufacture of slidable door panels, to equip the bottom margins of such panels with a fitting which includes a follower member designed for registration with the channel of a guide track on the floor. Fittings of the type just mentioned are satisfactory in instances where the distance between the bottom edge of the door panel and the guide channel is predetermined, and such space remains substantially constant as the panel is shifted between open and closed positions. However, in many instances, the vertical dimension of the door panel and the height of the door opening may vary to such an extent that when a conventional follower member is secured to the bottom edge of the door panel, imperfect registration of the follower member with the guide channel is experienced. Door panels of the type referred to above are usually suspended from a track on the underside of the door frame. Under such circumstances, there is a possibility that the lower edge of the door may not be properly spaced from the guide channel in the floor to accommodate conventional, non-adjustable channel follower fittings.

It is therefore one of the important objects of the present invention to provide a guide channel follower device for slidable panels such as suspended door panels whereby registration between a follower member carried by the panel and a guide channel in the floor will be maintained, even though the space between the lower edge of a suspended door panel and the guide channel may vary.

More specifically, the invention contemplates a guide channel follower device in which the follower member is constantly and resiliently urged in such a direction as to assure registration of the follower with a guide channel as the panel is shifted between open and closed position.

The foregoing and other objects and advantages will be more apparent from the following detailed description, when considered in connection with the accompanying drawing, wherein:

FIG. 1 is a plan view of hingedly-connected, accordion folding door panels of the type particularly adapted to accommodate a guide channel follower device of the type contemplated by the present invention;

2

FIG. 2 is an enlarged, fragmentary, vertical sectional view taken centrally of a guide channel follower device of the type herein described;

FIG. 3 is a vertical, sectional view taken substantially along the line 3—3 of FIG. 2;

FIG. 4 is a fragmentary, vertical sectional view similar to FIG. 2, disclosing the guide channel follower device of the invention in association with a modified guide channel or track which projects above the plane of a floor; and

FIG. 5 is a perspective, exploded view of the various parts which comprise the guide channel follower means shown in the other figures.

Referring now to the drawing more in detail, wherein like numerals have been employed to designate the similar parts throughout the various views, it will be seen that one embodiment of the invention consists of a guide channel follower device designated generally by the numeral 10. From the description which follows, it will be clear that this device 10 is attachable to the lower edge of a slidable panel such as a slidably-suspended door panel 12. The plan view in FIG. 1 illustrates one type of slidable door panel arrangement, namely an accordion foldable type, in which the lower edge of each panel is equipped with a guide channel follower device of the type designated by the numeral 10. This follower device cooperates with a floor track or guide channel 14. The door panels 12 are conventionally supported along their upper edges by a suitable fitting or carriage not shown, which slides along a track provided in the upper structure of a door frame 16.

The channel follower device 10 includes follower support means designated generally by the numeral 18. This follower support means 18 includes a plate-like portion 20 adapted to be secured to the bottom edge of a panel 35 by screw fasteners 22. A bearing or bushing member 24 forms a part of the follower support means 18 and extends upwardly from the plate 20. This bearing member 24 is preferably housed within a recess 26 provided in the lower edge of the panel 12. Slidably accommodated by the bearing 24, is a pintle or shank means 28. The upper extremity of the shank 28 is preferably enlarged as by peening to prevent unauthorized removal of the shank from the bearing 24. The lower or projecting portion of the shank 28 carries a guide roller or follower member 30. The lower extremity of the shank 28 is also peened so as to secure the follower member 30 against unauthorized dislodgement from the shank. Encircling the shank 28, immediately above the follower member 30, is a washer or follower disc member 32. Both the disc member 32 and the follower 30 are preferably formed of suitable plastic material such as nylon or the like, having the quality of self-lubrication. It will be noted that the disc 32 is mounted intermediate the follower 30 and a flange 34, formed integral with the shank 28.

Interposed between the upper surface of the flange 34 and the underside of the plate-like member 20 of the follower supporting means 18 is a resilient member in the form of a conically shaped coiled spring 35. This coiled spring 35 functions to continually urge the follower member 30 and its associated disc or washer 32 into proper registration and engagement with the guide channel 14. The follower roller 30 and the freely rotatable disc 32 may be shifted upwardly until the conical coiled spring 35 has been completely collapsed. The maximum degree to which the roller follower member 30 may be shifted downwardly will be determined either by the engagement of a peened shoulder 36 at the upper extremity of the shank 28, or by the engagement of the underside of the disc member 32 with the upper surface or surfaces of the channel member 14. It is preferred

to use a coil spring of the specific type shown in the drawing, wherein the lowermost convolution of smallest diameter engages the flange 34 and the convolution at the opposite extremity of the spring of larger diameter engages the underside of the plate-like member 20 thus to react upwardly against the plate-like member 20 and downwardly against the flange 34 and counter the weight of the suspended panels. By employing such a spring construction, each of the convolutions may be telescopically accommodated by the next adjacent convolution, assuming the form of a spiral, thereby affording the maximum extent of axial shifting of the pintle 28.

From the foregoing, it will be apparent that the guide channel follower means contemplated by the present invention is so arranged that the follower 30 and its associated disc member 34 will be maintained in registration engagement with the channel or guide track even though the space between said track and the lower edge of the door panel may vary. In other words, the follower member is self-adjustable so as to accommodate itself to various spacings between the lower edge of the door and the guide channel or track, within the limits determined, of course, by the extent to which the shank 28 may be longitudinally shifted. In FIG. 2, a guide channel 14 is shown in which the upper edge thereof is flush with the surface of the floor 38, whereas in FIG. 4, a modified channel 14a is disclosed which rests upon and projects somewhat above the plane of the floor.

Other structural embodiments are contemplated by the present invention. Various materials other than the plastic material referred to above may be used in the production of the disc 32 and associated follower roller 30. It is, of course, desirable to reduce as much as possible the friction resulting from the engagement of the washer 32 and roller 30 with the guide track. Both the disc 32 and the roller 30 are freely rotatable with respect to the shank 28, and hence are respectively readily slideable along and rotatable within the guide track.

The invention is claimed as follows:

1. A guide channel follower device for use in association with the lower margin of a slideable panel, as for example a door panel adapted to be suspended from above and to be shifted along a lower guide channel, said device including follower supporting means for attachment to the bottom edge of a panel to be guided, said follower supporting means including a bearing section for attachment to said lower panel edge, vertically disposed shank means in said bearing section, a portion of said shank means projecting axially below said bearing section, a guide channel follower member associated with the lower extremity of the projecting portion of said shank means, said follower member and shank being relatively axially shiftable with respect to said follower supporting means, and resilient means under compression biasing said follower member axially downwardly from

said supporting means whereby to maintain registration of the follower member with a complementary guide channel and reacting upwardly against the adjacent lower panel edge to counter the weight of the suspended panel.

5 2. A guide channel follower device as set forth in claim 1, wherein said follower member includes a rotary element located in the vicinity of the free lower extremity of said shank means.

10 3. A guide channel follower device as set forth in claim 1, wherein said shank means is longitudinally shiftable within said bearing section.

15 4. A guide channel follower device as set forth in claim 1, wherein means in the nature of a disc is provided for limiting the extent to which said follower member may be inserted within a complementary guide channel.

20 5. A guide channel follower device as set forth in claim 1, wherein the guide channel follower member includes a rotatable self-lubricating roller carried at the free lower extremity of said shank means, and a rotatable self-lubricating disc member encircling said shank means and presenting an annular guide track engaging surface.

25 6. In combination with the lower edge of a slidably suspended door panel and a guide track positioned adjacently beneath said lower edge, a guide channel follower device including follower supporting means attached to said lower panel edge, said lower panel edge provided with an aperture extending upwardly therefrom, a bearing member mounted within said aperture, a vertically disposed shank member in said bearing member and vertically shiftable with respect to said bearing member, a portion of said shank member projecting axially below said bearing member, a guide channel follower member associated with the lower extremity of said projecting shank portion, said follower member extending within and guided by said track, and resilient means under compression biasing said follower member axially downwardly whereby to maintain registration thereof with said track and reacting upwardly against the adjacent lower panel edge to counter the weight of the suspended panel.
